US00D956999S

(12) **United States Design Patent** (10) **Patent No.:** **US D956,999 S**
(45) **Date of Patent:** **** Jul. 5, 2022**

- (54) **PIPETTE TIP SHEET ASSEMBLY**
(71) Applicant: **BIOTIX, INC.**, San Diego, CA (US)
(72) Inventors: **Scott Edward Curry**, Carlsbad, CA (US); **Arta Motadel**, San Diego, CA (US); **Peter Paul Blaszczak**, San Diego, CA (US)
(73) Assignee: **BIOTIX, INC.**, San Diego, CA (US)
(**) Term: **15 Years**
(21) Appl. No.: **29/783,945**
(22) Filed: **May 17, 2021**
